UNITED STATES PATENT OFFICE

WILLIAM J. CAMPBELL, OF INDIANAPOLIS, INDIANA, ASSIGNEE TO AMERICAN SLICING MACHINE COMPANY, OF CHICAGO, ILLINOIS, A CORPORATION OF NEW YORK

SLICING MACHINE

Application filed May 10, 1930. Serial No. 451,811.

My invention relates to an improvement in slicing machines and particularly to an improvement in slicing machines of the type wherein the knife is employed, associated with generally parallel guard and gauge plates, and a carriage is guided across the face of guard and gauge plates and past the cutting edge of the knife. One object is the provision of means for thrusting the meat, upon the carriage, toward the gauge and guard plates and toward the knife, as the carriage is moved toward and past the cutting edge of the knife. Another object is the provision of yielding means for urging the work toward the knife. Another object is the provision of a pusher plate, which may be yieldingly actuated, and which is removable into and supportable in inoperative position. Other objects will appear from time to time in the course of the specification and claims.

I illustrate my invention more or less diagrammatically in the accompanying drawings, wherein—

Figure 1 is a front view of the machine; Figure 2 is a plan view with parts in section;

Figure 3 is an end view;

Figure 4 is an end view partly in section with parts in different positions;

Figure 5 is a section on the line 5—5 of Figure 4.

Like parts are indicated by like symbols throughout the specification and drawings.

Referring to the drawings, A generally indicates the base portion of a slicing machine frame, which may be provided with yielding studs or supports A¹.

In the form of my device herein shown I illustrate a rotary knife B with the knife shaft B¹ and the actuating pulley B², about which passes the belt B³ which may extend to a motor or any other suitable driving means. It will be observed that the axis of the shaft B¹ is somewhat tilted in a horizontal plane, as shown in dotted line in Figure 2.

The forward face of the knife is protected by a guard plate C, which serves to mask the knife save for the arcuate exposed portion B⁴ as shown in Figure 1. The tilting of the knife shaft B¹ tilts the plane of the edge of the

knife in relation to the plane of the guard plate C, whereby the exposed portion B⁴ of the knife may be advanced forwardly of the plane of the guard plate C.

D indicates a gauge plate and may be mounted for example upon a support D¹, which support is movable upon the base A, whereby the gauge plate may be set at various positions, in order to regulate the thickness of the desired slice.

E generally indicates the carriage structure which is mounted for example upon the cylindrical supporting track E¹ and is held against rotation in relation thereto, for example by the rectangular track E² which is engaged by the adjustable contact members E³ in the arms E⁴ which project downwardly from the carriage E. It will be understood that the tracks E¹ E² serve to guide the carriage along a path or excursion substantially parallel with the faces of the guard plate C and the gauge plate D.

In the form of my device herein shown a meat or work support generally indicated as G is pivotally mounted upon the carriage E, as at G¹. Referring to the support when it is in the position in which it is shown in Figure 1, it includes a horizontal work supporting portion G² and a vertical work engaging or work thrusting flange G³. In order to permit the device to be tilted in relation to the carriage, in order to convert the support into a V-trough, I provide links G⁴ pivoted as at G⁵ and slotted as at G⁶ to receive the locking knob G⁷ mounted upon the carriage E.

Associated with the work support G is the hollow guide rod H the forward end of which may be mounted for example in the member H¹, associated with the upstanding element or flange G³. Concentric with the rod H, and surrounding it, is the sleeve H², the sleeve being slidable upon the exterior of the rod. Positioned within the hollow of the rod H is a spring H³ one end of which is secured as at H⁴, in relation to the rod H and at abutment H¹. The other is secured to a cap H⁵ which may be screwthreaded into the end of the rod H², and which moves with it and is effectively unitary with it. The cap H⁵ is provided with the extending flange H⁶ of

greater diameter than the cylindrical exterior of the rod H^2 . The spring H^3 serves normally to hold the sleeve H^2 in the position in which it is shown in Figure 2, the inner end of the sleeve H^2 abutting against the member H^1 . H^1 is a guard plate secured to the member H^1 and flange G^3 .

Slidable along the cylindrical exterior of the sleeve H^2 is an outer sleeve J . The sleeve J is adapted to serve as a manual handle for the movement of the carriage E along the tracks $E^1 E^2$. Extending therefrom and over the flange G^3 is the extension J^1 which may form a unit with the manual handle J^2 which in turn connects with the sleeve J^3 through which passes the pin J^4 at the outer end of which is mounted any suitable pusher plate J^5 , whereby the work may be thrust across the face of the support G^2 , and against the gauge plate D . The pin J^4 may be screwthreaded and may have associated with it locking and adjusting nuts J^6 , whereby the position of the pusher plate J^5 in relation to the handle J^2 may be varied. In the form of my device herein shown the pusher plate is provided at each end of its lower edge with a downward projection J^7 in which may be mounted an anti-frictional member J^8 adapted to engage the upper surface of the member G^2 .

In the normal operation of my device it will be understood that, when the pusher plate is in employment, it may be drawn rearwardly to permit the work to be positioned upon the support G^2 . This retrograde manual movement of the pusher plate draws the sleeve J against the flange H^6 of the plug H^5 and moves the sleeve H^2 rearwardly upon the sleeve H , against the spring H^3 which tends tensionally to resist this movement. When the work has been positioned and this manual pressure is released, the spring H^3 urges the sleeve H^2 toward the cutting plane, and thereby moves the sleeve J and thus moves the pusher plate J^5 against the work, urging the work against the gauge plate D . This yielding thrust continues until the forward end of the sleeve H^2 engages the member H^1 . Thereafter the operator must manually thrust the pusher plate, which he may do by grasping either the sleeve J or the handle J^2 . In practice a convenient method is for the operator to place his fingers about the sleeve J , his fingers also abutting against the member J^1 . He may then exercise a slanting thrust, which serves at the same time to move the carriage for the cutting stroke, and to thrust the pusher plate against the work, and the work against the gauge plate.

It will be understood that the employment of the extensible guide above described for the sleeve J not only provides a yielding thrust for part of the excursion of the pusher plate, but permits the pusher plate to be employed with work which extends rearwardly from the gauge plate for the entire length

of the member G^2 of the support G^2 . In effect, extensible guiding means are employed for the sleeve J , ample to make the pusher plate usable throughout the entire length of the carriage or support. 70

The operator may prefer to dispense with the pusher plate, in which case he may withdraw the pusher plate to the position in which it is shown in Figure 4, enabling it to clear the support G^2 . The pusher plate may then be rotated into the dotted line position in which it is shown in Figures 1 and 3. It will be understood that the sleeve J , and with it the handle J^2 is rotatable about the sleeve or guide H^2 , and the pusher plate itself is rotatable in relation to the sleeve H^2 . Therefore the pusher plate will easily be rotated into the dotted line position of Figures 1 and 3. The operator may then release the pusher plate and permit the spring H^3 to contract. This contraction of the spring will hold the parts in the position in which they are shown in dotted line in Figure 3. In order to hold the pusher plate fixed in inoperative position, I may employ the guide or support K , as shown in Figures 3 and 4, with its outwardly extending horizontal portion K^1 upon which the lower edge of the pusher plate J^5 may be supported. The engagement of the handle J^2 or the connecting member J^1 with the edge of the support G^2 serves as a limit or stop. In order to limit the outward movement of the sleeve H^2 in relation to the sleeve H , I may employ the stop K^2 which slides in a slot K^3 in the sleeve H and is itself fixed upon the inner surface of the forward end of the sleeve H^2 . 100

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing. 105

The use and operation of my invention are as follows:

In a slicing machine of the type herein shown it is sometimes desirable, and in fact frequently desirable, to employ a pusher plate for thrusting the work toward the cutting plane, and against the gauge plate. I provide a pusher plate which is effective throughout the entire length of the support G^2 and which, initially, provides a yielding thrust, which is supplemented, as to the last few inches, by a manual thrust, effective after the engagement of the parts terminates the yielding thrust. When the operator wishes an unimpeded upper surface, as in decrusting bread, or when he is slicing materials which he wishes to hold manually, he can dispense with the pusher plate by with- 115

drawing it and rotating it in inoperative position. It will there remain, yieldingly held in inoperative position, as shown in dotted line in Figure 3.

I claim:

5 1. In a slicing machine which includes a knife and means for actuating it, a carriage, and means for guiding it past the cutting edge of the knife, a pusher plate mounted upon said carriage and a telescoping guide therefor, said guide including a fixed member and a member longitudinally movable therewith, the pusher plate being slidably mounted in relation to said movable member, a stop on said movable member adapted to be engaged by the pusher plate upon withdrawal of the pusher plate a predetermined distance from the cutting plane, said movable member being extensible a sufficient distance to permit the pusher plate to be withdrawn from above the carriage.

10 2. In a slicing machine which includes a knife and means for actuating it, a gauge plate, a carriage, means for guiding it across the gauge plate and past the cutting edge of the knife, a pusher plate mounted upon the carriage and an extensible guide therefor, including a fixed guide member, a movable guide member slidably thereon, and a pusher plate supporting means slidable upon the movable guiding member.

15 3. In a slicing machine which includes a knife and means for actuating it, a gauge plate, a carriage, means for guiding it across the gauge plate and past the cutting edge of the knife, a pusher plate mounted upon the carriage and an extensible guide therefor, including a fixed guide member, a movable guide member slidably thereon, and a pusher plate supporting means slidable upon the movable guiding member and rotatable in relation to the fixed member.

20 4. In a slicing machine which includes a knife and means for actuating it past the cutting edge of the knife, a pusher plate mounted upon said carriage and an extensible guide therefor, the pusher plate being rotatable about an axis co-incident with said guide, and a supporting member for said pusher plate extending transversely from said guide, the pusher plate being rotatably mounted in relation to said supporting member, the axis of rotation of the pusher plate in relation to said supporting member being laterally spaced from the axis of rotation of the pusher plate and member about the guide.

25 5. In a slicing machine which includes a knife and means for actuating it, a gauge plate, a carriage and means for guiding it past the cutting edge of the knife, a pusher plate mounted upon said carriage, and an extensible guide therefor, and means for yieldingly urging said pusher plate toward the cutting plane of the knife, said means becoming effective when the pusher plate is

30 withdrawn a predetermined distance from the cutting plane, said yielding means being associated with the extensible guide for the pusher plate, and tending normally to urge said guide toward non-extended position.

6 6. In a slicing machine which includes a knife and means for actuating it, a gauge plate, a carriage and means for guiding it past the cutting edge of the knife, a pusher plate mounted upon said carriage, and an extensible guide therefor, and means for yieldingly urging said pusher plate toward the cutting plane of the knife, said means becoming effective when the pusher plate is withdrawn a predetermined distance from the cutting plane, said guiding means including a fixed guiding member, a movable guiding member longitudinally movable in relation thereto, the pusher plate being movable upon said movable guiding member, stop means upon said movable guiding member adapted to be engaged by the pusher plate, the yielding means for the pusher plate being adapted to urge said movable member and pusher plate toward the cutting plane, said yielding means becoming effective when, in the course of the withdrawal of the pusher plate, the plate has engaged said stop means and withdrawn said movable guiding member along the fixed guiding member.

7 7. In a slicing machine which includes a knife and means for actuating it, a gauge plate, a carriage, and means for guiding it across the gauge plate and past the cutting edge of the knife, a pusher plate mounted upon said carriage and an extensible guide therefor, said extensible guide including a fixed guide member mounted on the carriage and a movable guide member movable thereon toward and away from the cutting plane, and yielding means adapted normally to urge said movable guide member toward the cutting plane, the pusher plate being mounted upon said movable guide member for movement in relation to said movable guide member toward and away from the cutting plane of the knife.

8 8. In a slicing machine which includes a knife and means for actuating it, a gauge plate, a carriage, and means for guiding it across the gauge plate and past the cutting edge of the knife, a pusher plate mounted upon said carriage and an extensible guide therefor, extensible guide including a fixed guide member mounted on the carriage and a movable guide member movable thereon toward and away from the cutting plane, and yielding means adapted normally to urge said movable guide member toward the cutting plane, the pusher plate being mounted upon said movable guide member for movement in relation to said movable guide member toward and away from the cutting plane.

of the knife, said fixed and movable guiding members being in telescopic relationship.

9. In a slicing machine which includes a knife and means for actuating it, a gauge plate, a carriage, and means for guiding it across the gauge plate and past the cutting edge of the knife, a pusher plate mounted upon said carriage and movable toward and away from the cutting plane of the knife and an extensible guide therefor adjustable to the desired range of movement of the pusher plate, said guide including a fixed guide member and a movable guide member mounted for movement on said fixed guide member toward and away from the cutting plane, and means adapted normally to urge said movable guide member toward the cutting plane, the pusher plate being movably mounted upon said movable guiding member for movement relative thereto toward and away from the cutting plane of the knife:

10. In a slicing machine which includes a knife and means for actuating it, a gauge plate, a carriage, and means for guiding it across the gauge plate and past the cutting edge of the knife, a pusher plate mounted upon said carriage movable toward and away from the cutting plane of the knife and an extensible guide therefor adjustable to the desired range of movement of the pusher plate, said guide including a fixed guide member and a movable guide member mounted for movement on said fixed guide member toward and away from the cutting plane, and means adapted normally to urge said movable guide member toward the cutting plane, the pusher plate being movably mounted upon said movable guiding member for movement toward and away from the cutting plane of the knife, and means for limiting the movement of said movable guiding member away from the cutting plane.

11. In a slicing machine which includes a knife and means for actuating it, a gauge plate, a carriage, and means for guiding the carriage across the gauge plate and past the cutting edge of the knife, a pusher plate mounted upon said carriage and movable toward and away from the cutting plane of the knife, and an extensible guide for the pusher plate, including a member fixed in relation to the carriage, and a cooperating member readily movable toward and away from the cutting plane, said guide being readily adjustable to the desired range of movement of the pusher plate, the pusher plate including a member slidably and rotatably mounted upon the movable member of said extensible guide for rotation about the longitudinal axis of said guide.

Signed at Indianapolis, county of Marion and State of Indiana, this 23rd day of April, 1930.

WILLIAM J. CAMPBELL.
